SAFETY MECHANISM FOR BOLT-ACTION FIREARMS

Harry L. Crockett, New Haven, Conn., assignor to
Olin Industries, Inc., a corporation of Delaware

Application September 1, 1944, Serial No. 552,241

1 Claim. (Cl. 42—3)

1

The present invention relates to improvements in safety-mechanisms for bolt-action firearms and relates more particularly to improvements in safety-mechanisms for types of firearms wherein a breech-bolt is employed which has both oscillatory or swinging movement laterally and reciprocating movement lengthwise of itself.

One of the objects of the present invention is to provide a superior firearm-construction wherein superior means is provided whereby the trigger is rendered ineffective in releasing the firing-mechanism until such time as the oscillating-and-reciprocating breech-bolt is in its full breech-closing position and effectively locked in such position.

Another object of the present invention is to provide a firearm with a superior construction and arrangement of parts whereby a breech-bolt of the character before referred to, may by turning movements in opposite directions respectively, render the firing-mechanism operative or inoperative.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of a bolt-action firearm embodying the present invention, with a portion of the receiver and a portion of the trigger-plate unit shown in section, and showing the breech-bolt closed and locked and showing the associated parts in the positions which they assume when the firearm is in readiness for being discharged;

Fig. 2 is a top or plan view thereof;

Fig. 3 is a view similar to Fig. 1 but with the action-slide omitted and showing the breech-bolt turned into its unlocked position to thereby cause the trigger to be, in effect, uncoupled from the sear;

Fig. 4 is a transverse sectional view taken on the line 4—4 of Fig. 1;

Fig. 5 is a view of the trigger-plate unit partly in plan and partly in horizontal section taken on the line 5—5 of Fig. 1 but with the hammer, hammer-plunger and hammer-spring omitted;

Fig. 6 is a similar view but taken on the line 6—6 of Fig. 3;

Fig. 7 is a view of the breech-bolt looking toward the rear end thereof;

2

Fig. 8 is a view in side elevation of the breech-bolt;

Fig. 9 is a perspective view of the control-plunger detached and on a larger scale;

Fig. 10 is a perspective view of the bell-crank lever detached on the same scale as Fig. 9;

Fig. 11 is a detached perspective view of the transmitting-member detached on the same scale as Figs. 9 and 10;

Fig. 12 is a detached perspective view of the sear on the same scale as Figs. 9 to 11 inclusive;

Fig. 13 is a similar view of the trigger;

Fig. 14 is a view in side elevation of a group of parts comprising the trigger, sear, transmitting-member, bell-crank lever and control-plunger; and

Fig. 15 is a top or plan view thereof.

The particular bolt-action firearm herein chosen for purposes of illustrating one form of the present invention includes a receiver 10, a barrel 11, a trigger-plate unit 12, an action-slide 13 and a breech-bolt 14.

The receiver 10 above referred to includes a top-wall 15 and integral side-walls 16 and 17.

25 The forward portions of the top-wall 15 and the side-wall 17 are cut away to provide an ejection-opening 18 which is closed by the breech-bolt 14 when the same is in its forward or breech-closing position but which is open when the said 30 breech-bolt is in its rearward position, in a manner common in the art.

The side-wall 16 of the receiver 10 is formed adjacent the forward end of the ejection-opening 18 with a forwardly-facing locking-abutment 19

35 which is adapted to be engaged by the rear face or edge of a bolt-locking lug 20 projecting radially from the left side of the breech-bolt 14 adjacent the forward end thereof. At a point substantially diametrically opposite its bolt-locking 40 lug 20, the breech-bolt 14 is formed with a second radially-projecting bolt-locking lug 21 which is adapted to have its rear face or edge engaged with a forwardly-facing locking-abutment 22 formed in the right side-wall 17 of the receiver

45 10.

Extending radially outwardly from the outer end of the bolt-locking lug 21 of the breech-bolt 14 is a bolt-operating lug 23 which projects into a cam-recess 24 formed in the inner-face of the 50 rear portion of the action-slide 13 adjacent the outwardly-projecting handle 25 thereof.

The bolt-operating lug 23 of the breech-bolt 14 and the cam-recess 24 in the action-slide 13 generally correspond to similar features embodied 55 in the well-known Garand military rifle, and co-

act in such manner that when the action-slide 13 is moved rearwardly from the position from which it is shown in Fig. 1, the said cam-recess will coact with the bolt-operating lug 23 to first rock the bolt in a clockwise direction (as viewed from the front) to disengage the bolt-locking lugs 20 and 21 respectively from the locking-abutments 19 and 22 of the receiver 10. Following this unlocking movement of the breech-bolt, the coaction of the bolt-operating lug 23 and the surfaces of the cam-recess 24 will then effect the direct rearward movement of the breech-bolt 14 until the latter reaches the limit of its rearward movement. Conversely, when the action-slide 13 is drawn forwardly, following the above-described rearward movement thereof, the coaction of the bolt-operating lug 23 and cam-recess 24 will first draw the said breech-bolt forwardly until such time as the respective rear faces of the bolt-locking lugs 20 and 21 thereof register with the locking-abutments 19 and 22 of the receiver 10, whereupon the breech-bolt will be turned transversely in a counterclockwise direction to again lock the breech-bolt in its breech-closing position.

On its right side, the breech-bolt 14 is formed with an integral longitudinally-extending rib 26, the under-face of which constitutes an actuating-surface 27 extending substantially the full length of the breech-bolt 14. The said actuating-surface 27 is adapted to engage with the flat upper surface of the head 28 of a vertical control-plunger generally designated by the reference character 29. The said control-plunger includes, in addition to its head 28, an integral downwardly-extending stem 30 which is cylindrically contoured and which is provided in its inner periphery adjacent its lower end with a coupling-notch 31. The said control-plunger 29 is mounted for vertical movement in a vertical passage 32 formed in the right side-wall of the trigger-plate unit 12. The said control-plunger 29 is yieldingly urged upwardly by a helical spring 33 which bears at its upper end against the under face of the head 28 and bears at its lower end against a suitable shoulder formed in the passage 32, as is especially well shown in Fig. 4.

Fitting into the coupling-notch 31 in the stem 30 of the control-plunger 29 is the cylindrically-contoured terminal of a substantially-horizontal arm 34 of a plate-like bell-crank lever generally designated by the reference character 35, which latter also includes a substantially-vertical arm 36, as is especially well shown in Fig. 10. The said bell-crank lever 35 is mounted for pivotal movement in a vertical plane upon a hammer-pin 37 extending transversely across the trigger-plate unit 12 and serving also to pivotally mount a hammer 38. The forward face of the vertical arm 36 of the bell-crank lever 35 engages with the rear face of a vertical finger 39 projecting upwardly from a bar-like transmitting-member generally designated by the reference character 40.

At its rear end, the transmitting-member 40 is formed with a lateral transmitting-arm 41 which projects into a rearwardly-and-laterally-opening coupling-notch 42 formed in the rear end of a sear generally designated by the reference character 43. The transmitting-arm 41 of the transmitting-member 40 reciprocates in a direction forwardly and backwardly with respect to the longitudinal axis of the firearm-structure, within the coupling-notch 42 in the sear 43, for purposes as will more fully hereinafter appear.

The sear 43 above referred to, is mounted for pivotal movement intermediate its respective opposite ends, upon the central portion of a trigger-pin 44 extending transversely across and supported in the rear portion of the trigger-plate unit 12. The said sear 43 fits between the laterally-spaced-apart upwardly - and - forwardly-projecting portions of side-flanges 45-45 of a trigger generally designated by the reference character 46. The said forwardly-and-upwardly-projecting portions of the side-flanges 45-45 are pierced to receive the trigger-pin 44.

The rear portions of the side-flanges 45-45 of the trigger 46 are respectively formed with one of two laterally-spaced-apart upwardly-facing transmitting-abutments 47-47 which are adapted, in a manner as will hereinafter appear, to coact with the under surface of the transmitting-arm 41 of the transmitting-member 40. The said trigger also includes an integral finger-piece 48 projecting downwardly from its rear-portion within a trigger-guard 49 forming a feature of the rear-portion of the trigger-plate unit 12.

In its upper rear-portion, at a point to the rear of its transmitting-abutments 47-47, the trigger 46 is formed with an upwardly-opening spring-pocket 50 receiving a trigger-spring 51 seated at its upper end against the under face of a guide-block 52 pinned to and upwardly projecting from the rear-portion of the trigger-plate unit 12, as is especially well shown in Figs. 1 and 3. The said trigger-spring exerts a constant effort to turn the trigger 46 in a counterclockwise direction, as required to yieldingly maintain its finger-piece 48 in its forward position.

The guide-block 52 above referred to is bifurcated at its upper end and receives, with a sliding fit, the cylindrically-contoured rear-portion of a hammer-plunger 53 having its forward end pivotally connected to the hammer 38 about midway the length thereof. Encircling the rear-portion of the hammer-plunger 53 intermediate the guide-block 52, and a rearwardly-facing shoulder 54 formed on the said plunger, is a helical hammer-spring 55 which exerts a constant effort to swing the hammer 38 in a clockwise direction, as required to engage the upper end of the said hammer with the rear end of a firing-plunger 56 mounted in the breech-bolt 14 in any approved manner well understood in the art.

The lower portion of the hammer 38 is formed with a rearwardly-facing cocking-abutment 57 which is releasably engaged by a forwardly-facing cocking-abutment 58 formed at the forward end of the sear 43. The said sear 43 is normally urged to turn in a counterclockwise direction so as to yieldingly maintain its cocking-abutment 58 in the path of movement of the cocking-abutment 57 of the hammer 38, by a sear-spring 59 (Figs. 1 and 3) having its upper-portion seated in a downwardly-opening spring-pocket 60 (Fig. 12) formed in the forward-portion of the sear 43. The lower end of the sear-spring 59 rests upon an adjacent upwardly-facing portion of the trigger-plate unit 12.

The sear 43 is also formed with a spring-pocket 61 (Fig. 12) opening rearwardly into the forward-portion of its coupling-notch 42 and accommodating a return-spring 62 which thrusts rearwardly against the forward face of the transmitting-arm 41 of the transmitting-member 40. In this connection, it is to be noted that the return-spring 62 is proportioned to apply a force mate-

rially weaker than the opposing force applied by the spring 33 of the control-plunger 29, for reasons as will hereinafter appear.

Operation

For purposes of making clear the operation of the safety-mechanism above described and illustrated in the accompanying drawings, let it be assumed that the parts are in the positions in which they are indicated in Figs. 1, 2 and 4, in which the hammer 38 is cocked, the action-slide 13 is in its full forward position, and hence the breech-bolt is locked in its breech-closing position.

Under the conditions above referred to, the longitudinal actuating-surface 27 of the breech-bolt will hold the control-plunger 29 downwardly against the tension of its spring 33, by force exerted upon the upper face of the head 28. When forced downwardly, the control-plunger 29 will swing the bell-crank lever 35 in a clockwise direction, and will thereby permit the return-spring 62 in the sear 43 to move the transmitting-member 40 rearwardly from the position in which it is shown in Figs. 3, 6, 14 and 15, into the position in which it is shown in Figs. 1 and 5.

The described rearward movement of the transmitting-member 40 will cause the transmitting-arm 41 thereof to ride over the upper surface of the transmitting-abutments 47-41 of the trigger 46, to thus place the firearm in condition for discharge.

Now when rearward draft is exerted upon the finger-piece 48 of the trigger 46, the transmitting-abutments 47-41 of the said trigger will engage with the under face of the transmitting-arm 41 of the transmitting-member 40 and will lift the rear end of the said transmitting-member upwardly. The upward movement of the transmitting-arm 41 of the transmitting-member 40 as just described, will cause the upper surface of the said transmitting-arm to thrust against the upper wall of the coupling-notch 42 in the rear end of the sear 43 and hence cause the said sear to be rocked in a clockwise direction around the trigger-pin 44 as a center. This rocking movement of the sear 43 will depress the cocking-abutment 58 at the forward end thereof and disengage the same from the cocking-abutment 57 of the hammer 38. The hammer 38 will thus be released to the action of the hammer-spring 55 and will strike the projecting rear end of the firing-plunger 56 to drive the same forwardly and thus effect the discharge of the firearm.

The action-slide 13 may now be either manually or automatically operated, and upon being moved rearwardly from its foremost position, following the discharge of the firearm, the said action-slide will, through the intermediary of its cam-recess 24 and the bolt-operating lug 23 of the breech-bolt 14, cause the said breech-bolt to first swing in a clockwise direction (as viewed from the front of the firearm), to thereby lift the bolt-locking lug 21 of the breech-bolt 14 and depress the bolt-locking lug 20 thereof respectively out of engagement with the locking-abutments 22 and 19 of the receiver 10. The breech-bolt will now have assumed the position in which it is shown in Fig. 3.

The clockwise turning movement of the breech-bolt 14 as above described, will lift the rib 26 and its downwardly-facing actuating-surface 27 and thus permit the spring 33 to raise the control-plunger 29 upwardly from the position in which it is shown in Figs. 1 and 4 into the posi-

tion in which it is shown in Figs. 3 and 14. This upward movement of the control-plunger 29 will turn the bell-crank lever 35 in a counterclockwise direction, thereby causing the vertical arm 36 of the latter to act through the vertical finger 39 of the transmitting-member 40, to shift the said transmitting-member forwardly against the relatively-light tension of the return-spring 62.

By means of the above-described action, the transmitting-member 40 will be bodily moved forwardly from the position in which it is shown in Figs. 1 and 5 into the position in which it is shown in Figs. 3, 6, 14 and 15.

After the breech-bolt 14 has been turned in a clockwise direction and unlocked as above described, and has permitted the forward movement of the transmitting-member 40 under the urge of the return-spring 62, the continued rearward movement of the action-slide 13 will, through the intermediary of its cam-recess 24 and bolt-operating lug 23 of the breech-bolt 14, cause the direct rearward travel of the said breech-bolt.

The direct rearward travel of the breech-bolt to the limit of its rearward travel, will effect the extraction and ejection of the just-fired cartridge and will also effect the counterclockwise swinging movement of the hammer 38 to re-cock the latter. During all of this rearward travel of the breech-bolt, the trigger 46 is uncoupled from the sear 43, due to the fact that the transmitting-member 40 is in its forward position.

Following the full rearward movement of the breech-bolt to re-cock the hammer 38 and extract and eject the just-fired cartridge, the action-slide 13 may be moved forwardly to similarly-move the breech-bolt 14. Prior to moving the breech-bolt 14 forwardly as just described, a fresh cartridge will be presented in front of it, either manually or by any suitable magazine (not shown). During all of the travel just referred to, the trigger 46 remains uncoupled from the sear 43, so that at no time during this interval can the hammer 38 be released by the operation of the trigger 46.

As soon as the breech-bolt reaches substantially its full forward or breech-closing position, the rear faces of the bolt-locking lugs 20 and 21 thereof will be brought respectively into registry with the locking-abutments 19 and 22 of the receiver 10. When the breech-bolt 14 has been moved into the position just described on its return to its breech-closing position, the next action of the forward movement of the action-slide 13 will be (through the intermediary of its cam-recess 24 and the bolt-operating lug 23 of the breech-bolt) to turn the breech-bolt in a counterclockwise direction, to thus lift its bolt-locking lug 20 into engagement with the locking-abutment 19 of the breech-bolt and to coincidentally depress the bolt-locking lug 21 of the breech-bolt into engagement with the locking-abutment 22 of the receiver 10.

The counterclockwise turning movement of the breech-bolt as just above described, will also depress the longitudinal downwardly-facing actuating-surface 27 thereof and similarly depress the control-plunger 29 against the tension of its spring 33. The described downward movement of the control-plunger 29 will turn the bell-crank lever 35 in a clockwise direction, thus swinging the vertical arm 36 thereof rearwardly. The turning movement of the bell-crank lever just referred to will permit the return-spring 62 of the sear 43 to force the transmitting-member 41 rear-

wardly, to place the transmitting-arm 41 over the transmitting-abutments 47—47 of the trigger 46 to again couple the said sear 43 to the said trigger. The shifting of the transmitting-arm 41 of the transmitting-member 40 into operative relationship with respect to the transmitting-abutments 47—47 will not take place, however, until the bolt-locking lugs 20 and 21 of the breech-bolt 14 have been turned sufficiently to effect the secure locking of the breech-bolt in its breech-closing position. Furthermore, the movement of the transmitting-member, as just described, cannot occur until rearward draft is released upon the finger-piece 48 of the trigger 46, since otherwise, forwardly-facing stop-abutments 63—63 respectively formed on the side-flanges 45—45 of the trigger 46, will check such movement of the said transmitting-member.

Thus, the sear 43 remains uncoupled from the trigger 46 and the latter remains inoperative until such time as the breech-bolt is locked in its breech-closing position, to thus guard against premature discharge of the firearm, which would be apt to not only cause damage to the firearm but injure the user by occasioning the bursting of a partly-seated cartridge.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

A firearm including in combination: a frame-structure having a bolt-receiving chamber therein and a forwardly-facing bolt-locking abutment; a breech-bolt constructed and arranged to both oscillate laterally in the bolt-receiving chamber of the said frame-structure and to reciprocate longitudinally therein, the said breech-bolt being

formed with a rearwardly-facing bolt-locking abutment constructed and arranged to be engaged with the bolt-locking abutment of the said frame-structure by a lateral turning movement 5 of the said breech-bolt, the said breech-bolt also being formed with an actuating-surface facing substantially downwardly and located on one side of the breech-bolt so as to move substantially vertically as the breech-bolt is oscillated; a vertically-movable plunger carried by the said frame-structure in a plane to one side of the center of oscillation of the breech-bolt and having a portion positioned to be engaged and depressed by the said actuating-surface of the said breech-bolt when the latter is turned into position to engage its aforesaid bolt-locking abutment with the bolt-locking abutment of the said frame-structure; spring-means urging the said plunger upwardly; a firing-member carried by the said frame-structure; a sear also carried by the said frame-structure and engageable with the said firing-member to releasably hold the same in its cocked position; a trigger carried by the said frame-structure; a transmitting-member also 25 carried by the said frame-structure and movable in a plane substantially longitudinal thereof, the said transmitting-member having a transmitting-portion constructed and arranged to be operatively interposed between a portion of the said trigger and a portion of the said sear to transmit the movement of the former to the latter; and a bell-crank lever operatively interposed between the said vertically-movable plunger and the said transmitting-member and constructed and arranged 30 to operatively interpose the transmitting-portion of the said transmitting-member between the said trigger and the said sear when the said plunger is moved downwardly by the turning movement of the said breech-bolt into position to engage its bolt-locking abutment with the bolt-locking abutment of the said frame-structure.

HARRY L. CROCKETT.
